M. GREENBERG

TRUNK HANDLE

Filed May 10, 1927

UNITED STATES PATENT OFFICE.

MORRIS GREENBERG, OF JERSEY CITY, NEW JERSEY.

TRUNK HANDLE.

Application filed May 10, 1927. Serial No. 190,187.

This invention relates in general to handles for receptacles and more particularly to trunk handles, one object of the invention being to provide a handle of this character which has a flexible and soft grip portion, such as leather, and embodying novel and improved features of construction whereby the said grip portion is protected against wear by contact with the metal or harder portions of the receptacle or trunk and against injury by contact with the floor or ground as when the trunk is stood on end or pushed about with the handle on the underside.

Another object is to provide a handle of the type including a flexible and soft grip portion, having slots at its ends through which pass metallic studs or bolts for securing the handle to a receptacle, wherein said slots are reinforced or lined by metal eyelets or the like and a flexible metal strip extends longitudinally of said grip portion on the outer side thereof and has its ends secured in said eyelets or metal reinforcements, so that the eyelets reinforce the grip portion against wear and being torn by said studs or bolts and said metal strip protects the soft grip portion against contact with the floor or ground, assists in straightening or flattening said grip portion normally against the side of the receptacle, and assumes a portion of the strains on the grip portion during lifting of the receptacle.

Other objects are to provide a novel and improved metal reinforcement or eyelet for trunk handles of the character described; to provide a handle having a novel and improved construction which is durable, artistic so as to enhance the beauty of the trunk, and simple and inexpensive, and to obtain other advantages and results as will appear from the following description.

Referring to the accompanying drawings in which corresponding and like parts are designated throughout the several views by the same reference character,

Figure 1 is a perspective view of a trunk handle embodying my invention showing the same applied to a trunk;

Figure 2 is a detached perspective view of the face side of the grip portion of the handle;

Figure 3 is a similar view of the rear side of the grip portion;

Figure 4 is an enlarged horizontal sectional view taken on the line 4-4 of Figure 1;

Figure 5 is a detached perspective view of one of the metal reinforcing eyelets before its application to the handle, and

Figure 6 is a plan view of the blank from which the eyelet is formed.

Specifically describing the illustrated embodiment of the invention, the reference character A designates the grip portion of the handle which is preferably formed of flexible soft material such as leather, and which has its ends secured as at C to the trunk or other body B to be lifted or carried by the handle.

In the present instance the ends of the grip portion A have longitudinal slots 1 into which loosely pass studs 2 projecting from the inner sides of substantially U-shaped clamps or clips 3 which have their ends secured to the trunk by rivets or bolts 4. The ends of the grip portion A underlie the clamps 3 and the studs 2 serve to connect the grip portion to the trunk. Normally the grip portion lies flat against the trunk as shown in Figures 1 and 4 of the drawings, but it may be flexed outwardly from the trunk to permit a handhold thereon by relative movement of the ends of the grip portion and the clamps 3 permitted by the loose arrangement of the studs 2 in the slots 1.

In accordance with the invention the slots 1 are reinforced by metal eyelets D each of which preferably consists of a single piece of sheet metal stamped to the shape illustrated in Figure 6. Thus, each eyelet includes a main or body portion 5 from the longitudinal edges of which project ears 6 portions of which as indicated at 7 are returned upon the body portion and other portions 8 of which are disposed at substantially right angles to the body portion.

From the center of the body portion is stamped an ear 9 which forms the eyelet opening 10 and one end of which is integral with the body portion 5 at one end of said opening. At the end of the body portion opposite the ear 9 is another ear 11 which has a portion 12 returned upon the body portion and another part 13 disposed at substantially right angles to the body portion. The eyelets are fitted into the slots 1 with the body portion 5 at the outer or face side of the grip portion A and the ends of the ears 6, 9, 11 bent or clinched against the rear side of the grip portion as shown in Figure 3. With such a construction it will be obvious that the material of

the grip portion will be prevented from contact with the clamps 3 and studs 2 and the walls of the slots 1 will be reinforced by the eyelets against wear and strains incident to use of the handle in lifting the trunk.

For protecting the face side of the grip portion from contact with the ground or floor when the trunk is stood on end, and also to assist in holding the grip portion normally flat against the trunk and to reinforce the grip portion against strain incident to lifting the trunk, a resilient metal strip 14 is arranged on the face side of the grip portion and has its ends connected to the eyelets D for movement relative thereto. In the present instance the body portions of the eyelets are formed with loops 15 and the ends of the strip 14 pass through said loops and are returned upon the strip as shown in Figures 2 and 4. Preferably the strip is secured as by a rivet 16 to the grip portion, but the ends of the strip have a sliding connection with said eyelets to permit flexing of the grip portion. With this construction, it will be obvious that a strip 14 will prevent any scratching or rubbing of the leather grip portion upon the ground or a floor, and the inherent resiliency of the strip will tend normally to flatten or straighten the grip portion. Also when the grip portion is in use for lifting the trunk, some of the strain is assumed by the strip 14.

The metal eyelets and the strip 14 add materially to the beauty of the trunk, harmonizing with the regular hardware of the trunk, and add to the suggestion of strength or ruggedness.

Of course, the strip 14 may be connected to the eyelets in other ways than that illustrated, and the eyelets may be made in different forms. I am aware that reinforcement of the slots of a trunk handle is not broadly new, and that metal strips have been utilized in handles for trunks and other articles; and while I do not desire to be understood as attempting to claim such old struc-

tures, the detail construction of my invention is susceptible of modification and changes by those skilled in the art without departing from the spirit or scope of the invention. Therefore, I do not desire to be understood as limiting myself except as required by the following claims when construed in the light of the prior art.

Having thus described the invention, what I claim is:

1. The combination with a body to be carried, of a handle comprising a flexible grip portion having longitudinal slots in its ends, metal reinforcing eyelets in said slots, means including a stud disposed in each of said slots for securing said grip portion to said body so that said grip portion may lie substantially flat against said body or be flexed outwardly therefrom, and a spring strip extending longitudinally of said grip portion and having its ends connected to said eyelets for relative movement.

2. The combination with a body to be carried, of a handle comprising a flexible grip portion having longitudinal slots in its ends, metal reinforcing eyelets in said slots, each comprising a body portion having a central opening and a plurality of integral ears extending at right-angles to said body portion and spaced from the edges of said portion, said body portion being disposed upon the face side of said grip portion and said ears extending through said slots and having their free ends clinched over the rear side of said grip portion, each of said eyelets having a loop projecting from said body portion, a resilient metal strip on the face side of said grip portion having its ends returned upon itself and passing loosely through said loops, and means including a stud disposed in each of said slots for securing said grip portion to said body so that said grip portion may lie substantially flat against said body or be flexed outwardly therefrom.

MORRIS GREENBERG.
